ARTICLE OF LUGGAGE OR SIMILAR ARTICLE

Sol Koffler, Providence, R. I.

Application June 27, 1955, Serial No. 36,702

Term of patent 14 years

(Cl. D87—5)

FIG. 1

FIG. 2

FIG. 3

FIG. 4

FIG. 5

Fig. 1 is a top plan view of an article of luggage or similar article, embodying my new design;

Fig. 2 is a front elevational view thereof;

Fig. 3 is an end view thereof;

Fig. 4 is a bottom plan view thereof; and

Fig. 5 is an enlarged view thereof showing the raised strip with recessed seam which completely circumscribes said article adjacent opposing sides thereof.

The dominant features of my design reside in the portions shown in full lines.

I claim:

The ornamental design for an article of luggage or similar article, as shown and described.
